(57) CLAIM

The ornamental design of the jewelry arrangement, as shown and described.

DESCRIPTION

FIG. 1 is a top view of an exemplary embodiment of a jewelry arrangement showing my new design;

FIG. 2 is top perspective view of the jewelry arrangement of FIG. 1; and,

FIG. 3 is a side view of the jewelry arrangement of FIG. 1. The broken lines are provided for illustrative purposes only, and form no part of the claimed design. In addition, the portions of the jewelry arrangement that are not shown in the drawing do not form any part of the claimed design.
